UNITED STATES PATENT OFFICE.

PATRICK D. RIORDAN, OF NEW YORK, N. Y.

SNOW-DESTROYER.

980,564.

Specification of Letters Patent.

Patented Jan. 3, 1911.

Application filed September 9, 1910. Serial No. 581,264.

To all whom it may concern:

Be it known that I, PATRICK D. RIORDAN, a citizen of the United States, residing in the borough of Manhattan, in the city, county, and State of New York, have invented certain new and useful Improvements in Snow-Destroyers, of which the following is a specification, reference being had to the accompanying drawings.

10 This invention relates to improvements in apparatus for destroying snow; and an object of this invention is to provide an apparatus of the character just referred to which will be comparatively simple in construction and which will be most efficient in use.

Apparatus to improvements in which this invention relates find their widest field of usefulness in large cities from the much 20 traveled streets of which the snow must be speedily removed to the end that traffic may not be impeded. In such cities water is supplied to hydrants at street corners or other convenient points along the highways 25 for the purpose of affording protection in case of fire. In carrying out my invention advantage is taken of this provision of water under pressure by equipping my new apparatus with means for supplying water to 30 the snow; and, in its preferred form, my new apparatus is fitted with mechanism for triturating the snow and this triturating mechanism may be driven by water flowing from the hydrant. The snow-destroying 35 mechanism will be mounted upon a vehicle; and this vehicle may be self-propelled, the propelling mechanism being adapted to be thrown into and out of engagement with the mechanism which drives the snow-de- 40 stroying machinery. An engine, however, may be used to drive the latter and the exhaust from this engine may be led to the same so that the heat of the exhaust may be used in reducing the snow to the form of 45 water. Since the water flows through the apparatus at a high velocity and is constantly agitated by the triturating devices, there is no danger of the apparatus becoming clogged due to freezing.

50 Other features of this invention will be pointed out in the detailed description which follows.

In the drawings illustrating the principle of this invention and the best mode now 55 known to me of applying that principle, Figure 1 is a central longitudinal sectional

view through my new snow destroyer, the engine mechanism being shown in full; Fig. 2 is a top plan view, parts being broken away for clearness of illustration; Fig. 3 60 is a bottom plan view; Fig. 4 is a detail showing the hopper, disintegrator and conveyor on an enlarged scale; Fig. 5 is a detail showing the manner in which the knives of the disintegrator are fastened in place; Fig. 6 65 is a detail showing in top plan view the lower guard-rod supporting-ring; Fig. 7 is a detail of a grating hereinafter described; Fig. 8 is a detail in perspective showing the ribs of the grating of Fig. 7 inverted and 70 edged at the bottom; Fig. 9 is a section on the line A—A of Fig. 1; Fig. 10 is a detail in perspective of the sweep shown in Fig. 9; Fig. 11 is a detail in perspective of the 75 knives of the triturator and their mountings; Fig. 12 is a detail which shows in cross-section a knife of the triturator; and Fig. 13 is a detail showing the manner in which the triturator is mounted in the tank.

The apparatus as a whole is mounted upon 80 and is carried by a truck-frame or chassis *a* which is, in turn, supported upon the axles *b*, *b'*. These parts are, however, shown in only a conventional way and without any attempt at detail, since the particular construction of the supporting road-vehicle is no part of this invention and the best practice in road-vehicle construction will in any event be followed. The vehicle may be self-propelled and such an arrangement of parts 85 is shown in the drawings, wherein the engine *d* drives the flexible shaft *d'* on the rear end of which is mounted a bevel gear *d''* that meshes with the bevel gear *e* which is mounted loose or idle upon the transverse 90 shaft *e'*. On the latter are mounted fast a pair of sprocket-wheels *c''* which by means of sprocket-chains *c'*, are connected with the rear wheels *c* mounted on the rear axle *b*.

The chassis *a* supports the casing or housing *f* on the annular top *f'* of which is fastened the ring *m* of a spider *m* the arms *m'* of which are integral with the latter and connect the same to the hub *m''* of the spider. To the ring *m* is secured the casing 100 *g* of a water-motor or water-wheel *h*. The latter turns in a chamber *i* which is closed at the top by a cover *k* provided with an air-tight manhole cover *k'*. The bottom of the chamber *i* is open, since it is formed by the spider-arms *m'* just referred to. The hub *m''* of the spider *m* serves as a bearing 105 110

for the hub h' of the water wheel h the buckets h'' of which ride on rollers h^* mounted on the ring m^* of the spider m . Through a hole in the hub m'' of the latter extends 5 the upper end of a solid driving shaft n which is vertically and centrally disposed and on the upper end of which is fastened the hub h' of the water-wheel h just referred to. Around the casing g of the water- 10 wheel h extends a water-pipe o at suitable intervals along which are arranged nozzles p that project inwardly through the casing g into close proximity to the buckets h'' of the water-wheel h . One end of the pipe o 15 is connected by sections of hose-pipe q with a suitable source of water-supply, as the hydrant r . It is obvious that, when the water under pressure flows through the pipe o and is discharged through the nozzles p , 20 the energy of the streams of water flowing from the latter will be expended in driving the water-wheel h and thereby the main driving shaft n .

To the shell-like casing f at the back and 25 near the bottom thereof is fastened an L-shaped bracket s on the horizontal part of which is seated and firmly fastened in place by bolts x a two-part or split ring t in the top flange t' of which are fastened, as hereinafter described, the lower ends of guard- 30 rods u the upper ends of which are held in the bottom flange v' of a split ring v . The guard-rods u and the split rings t, v form a stationary but removable cage the purpose 35 of which will be hereinafter explained. Wirework 106 may be placed at the bottom of the guard-rods u to prevent the passage of stones and the like. Inside of the ring v is seated the lower or base end of the conveyer-casing y to which the parts of the ring v are fastened by bolts w . The casing y rises vertically upward and in it is mounted 40 a helical or screw conveyer z . The base end of the conveyer-casing y is enlarged and is formed with a shoulder y' over which fits the inwardly-projecting top flange v'' of the ring v , whereby the base end of the conveyer-casing is held rigidly in place. The top v'' of the latter is inclined from the rear 45 slightly upward and a downwardly-inclined chute 2 leads from the upper end of the conveyer-casing to the chamber i in which turns the water-wheel h , the lower or discharge end of the chute 2 entering through 50 an opening in the dome-shaped cover k and having a flaring or trumpet-shaped mouth 3 to facilitate the discharge. Further, the chute 2 gradually increases in size from its upper to its lower end to facilitate the passage 55 of the snow. To keep the mouth 3 clear and unobstructed, the arms h^* of the water-wheel h is provided with inclined blades or vanes i' which sweep across the mouth 3 and carry away the snow, which then falls 60 between the arms h^* .

Between the lower end of the screw-conveyer z and the guard-rods u is mounted a cylindrical cutter or disintegrator 4 consisting of the upper ring 5, the lower ring 6 and the knives 7 the ends of which are firmly fitted in the slots 8 in the rings 5, 6 and are formed with flanges 7' fastened thereto. The knives are closer together at their inner edges than at their outer edges, whereby it results that the channels or openings 9 between the knives 7 are slightly wider at the outside than at the inside of the cutter 4. The lower ring 6 is carried by the outer ends of the spider-arms 10 of the spider 11 and is formed with a central web or bottom-plate 12 which closes the cutter 4 at the bottom and is formed with an opening 12' adapted to be closed by a shutter 12''. By opening the latter the space above the bottom-plate 12 may be cleaned out. The outer edge portion of the lower ring 6 projects slightly beyond the outer edges of the knives 7 and extends under the top flange t' of the lower ring t in which are mounted the guard-rods u . 90

To each side of the chassis a near the rear end thereof is fastened an end of a transversely-disposed bracket 13 near the middle of which is pivotally mounted the lower end of the conveyer-shaft z' . The lower part of 95 the latter extends through a central opening in the bottom plate 12 of the cutter 4 and lies within a hollow shaft 14 to the upper end of which is fastened the hub 11' of the spider 11 and on the lower end of which is mounted 100 fast a bevel gear 15. A collar 16 on the conveyer-shaft z' furnishes a bearing to steady the lower end of the hollow or sleeve shaft 14, which serves to turn the cutter 4 in a direction opposite to that in which the 105 screw-conveyer z is rotated by the shaft z' . The latter and the hollow shaft 14 are driven in the following manner: Extending lengthwise of the chassis a is a shaft 17 which is rotatably mounted in hangers 18 110 that depend from the chassis a . The front end of this shaft 17 carries a bevel gear 19 which meshes with a bevel gear 20 on the lower end of the driving shaft n ; and the rear end of this shaft 17 carries a bevel gear 21 which meshes with a bevel gear 22 on the lower end of the conveyer-shaft z' . Mounted in the hangers 18 and above the shaft 17 is the rotatable shaft 23 on the rear end of 115 which are fastened the pinion 24 and the bevel gear 25. The latter meshes with a bevel gear 15 on the lower end of the hollow shaft 14, while the pinion 24 meshes with a spur gear 27 on the shaft 17. The bevel gears 19, 20, the shaft 17 and the bevel gears 21, 22, transmit the rotatory motion of the main driving shaft n to the conveyer-shaft z , while the shaft 17 through the spur gear 27 and pinion 24 drives the upper shaft 23 and through the latter and the bevel gears 120 130

25, 15 turns the hollow shaft 14 and thereby the cylindrical cutter or disintegrator 4.

Surrounding the guard-rods u and spaced a suitable distance therefrom is the wall of 5 a frusto-conical hopper 28 the bottom of which is formed with an opening 29 to permit the passage of the lower ends of the guard-rods u . The ring t is formed at its top with upwardly and outwardly inclined 10 lip t'' giving to the ring a flaring or trumpet-shaped annular top within which lies the bottom edge of the hopper 28. At its upper edge the hopper 28 is hung in the bracket-lugs 30 free to swing on the rear of the casing f . Extending upwardly and rearwardly from the transverse bracket 13 is an 15 arm 31 on the free upper end of which is pivotally mounted a toothed disk 32 which meshes with the spur gear 33 fast on the hollow shaft 14. The upper face of the toothed disk 32 is ribbed or corrugated and upon it rests a roller 34 carried by the lower end of the leg or post 35 which extends 20 downwardly from the bottom of the hopper 28. A coil spring 36 serves to hold the roller 34 firmly against the ribbed upper face of disk 32 and, as the latter is turned by the spur gear 33, a vibratory or shaking motion of the hopper is produced. In this way 25 the snow is shaken down toward the guard-rods u and the cutter 4.

Just below the junction of the chute 2 with the upper part of the conveyer-casing y there is mounted on a ledge y' in the latter a grating 37 the ribs or bars 38 of which are beveled or edged on the lower face of the grating. The top of the screw-conveyer z lies in close proximity to this lower face and, should pieces of ice or other hard substance become wedged in between the ribs 38 and the screw-conveyer z , they will be crushed into fragments so small that they will pass through the small openings in the grating 37. Above the latter is mounted a 35 sweep 39 consisting of spider-arms 40 which carry hoops or bands 41. These rings 41 carry blades or vanes 42 which, together with the spider-arms 40 are provided with pins 43. The outer ends of the spider-arms 40 are provided with plates or strips 40*. This sweep serves to throw the snow into the chute 2 and to keep the top of the grating 37 clear, as well as to disintegrate or 40 triturate the snow still further. Just above 45 the grating 37 and outside of the sweep 39 there is mounted a semi-circular water-pipe 44 which is connected with the water-pipe o and which is formed with the perforations 45 on its outside, whereby the streams or 50 jets of water flowing through these perforations are directed toward the chute 2.

The driving shaft n extends through a hollow shaft 46 the upper end of which turns in a bearing in the hub m'' of the spider m 55 and the lower end of which is formed with

a collar 47 supported in a ball-bearing 48 in transverse girders 49 which extend from side to side of the chassis a . On the lower end of the hollow shaft 46 is mounted a bevel gear 50 which meshes with a bevel gear 51 on the front end of the shaft 23.

The driving shaft n and the hollow shaft 46 extend through and are centrally disposed within the shell 52 of a triturator 53. The shell 52 is formed at its upper edge or 75 top portion with an outwardly-extending flange 52' which is fastened in any suitable way to the top f' of the casing f . The triturator 53 is supported on legs 54 the lower ends of which are fitted in recesses 55 80 formed in the bedplate 56 which constitutes the bed of the truck. Within the shell 52 and with its edges in as close proximity thereto as possible without touching the same, there is mounted on the hollow shaft 85 46 at the top thereof a screw-conveyer 57. Immediately below the latter there is mounted within and fastened to the shell 52 a horizontally-disposed knife-carrying grating 58 consisting of radially-extending 90 spider-arms 59, which are formed with recesses 60, in which are fitted a series of concentric rings 61. At the bottom of the shell 52 there is seated therein and held by studs 62* another horizontally-disposed knife-carrying grating 62 which is similar in construction to the knife-carrying grating 58. About midway between these stationary gratings 58, 62, there is mounted on the hollow shaft 46 a horizontally-disposed knife-carrying grating 63 which rotates with the shaft 46. In the stationary gratings 58, 62 100 are mounted the base ends of the double-edged knives 64, the knives carried by the grating 58 extending toward the knives of 105 the stationary grating 62 and the knives of both stationary gratings 58, 62 extending to within a short distance of the rotary grating 63. Similarly, the points of the knives 65 carried by the latter lie within only a very 110 short distance from the stationary grating opposed to those points. The arrangement of these knives 64, 65 is such that only a narrow interval separates knives adjacent to one another; and in order to prevent any 115 collision between the stationary knives 64 and the moving knives 65 and to hold these knives in place, they are bound with hoops or bands 66. The grating members 59, 61 are triangular in cross-section and an edge 120 is presented by them to the falling snow, in order to insure the latter's free passage downward.

Between the shell 52 of the triturator 53 and the casing f is arranged the shell or wall 125 67 of a tank 68 the bottom of which forms a part of the bedplate 56 of the truck. The wall 67 is substantially concentric with the wall 52 of the triturator 53 and its upper edge or top portion lies a short distance be- 130

low the top f' of the casing f . The latter is at its lower portion cut away from front to rear along the lines 69 in Fig. 1, from which it results that the bottom of the casing f is formed by a pair of helically-disposed surfaces down which the water and finely-divided snow flow from the tank 68 and are discharged into a forwardly and downwardly inclined chute 70. Within the latter 10 is rotatably mounted a shaft 71 on which are arranged the blades or paddles 72, the outer ends of which lie in a helix described about the shaft 71 as an axis. The shaft 17 carries a sprocket-wheel 73 which is connected by the chain 74 with a sprocket-wheel 75 fast on the rear end of the shaft 71, whereby the latter is driven. The action of the paddles or blades 72 is to pulverize any snow particles suspended in the water flowing through the chute 70 and to force the liquid mass to its discharge end. A flexible conduit or hose-pipe 76 coupled to the front end (or discharge end) of the chute leads the water to the usual drain provided at the 25 street-corner.

The top f' of the casing f is provided with an air-tight handhole cover f'' by the removal of which access may be obtained to the upper end of a slide-rod 77 to the lower 30 end of which is attached a slidable plate or door 78 which covers an opening in the wall 67 of the tank 68 at the bottom thereof. By pulling the slide-rod up so as to raise the plate 78 above the opening, the liquid contents of the tank 68 will be permitted to flow into the chute 70 and thence through the hose-pipe 76. The wall 67 of the tank 68 is further formed with an opening 79 provided with a cover-plate 80. By removing 40 the latter, access may be obtained to the space below the lower stationary grating 62 of the triturator 53 and a hook-shaped bar or other suitable implement may be used to remove the solid material which may have 45 there collected.

In case the snow in the street is in a melting or slushy condition, the hopper 28 may be detached from the bracket-lugs 30 and lowered, after removing the leg 35 and 50 spring 36, so that its lower edge fits snugly against the lip t' of the ring t . A valve-controlled pipe or conduit 81 connects the hopper 28 with the rear end of the discharge chute 70. During a thaw the slush may be 55 drained directly from the hopper 28 into the latter through the pipe 81.

Journaled in hangers 82 is a stub-shaft 83 on the inner end of which is mounted fast a bevel gear 84 which meshes with a bevel 60 gear 85 fast upon the lengthwise extending shaft 17. By engaging a crank-handle 86 (shown in dotted lines in Fig. 2) with the outer end of the stub-shaft 83, the latter may be turned by hand power and the shafts 65 n , z , 14 and 46 driven thereby in an emer-

gency or under circumstances in which the use of other power is impracticable or undesirable.

In case water-power is not available to drive the water-motor h , or in case it be 70 found desirable to assist the latter in driving the shaft n and the parts connected with the same, the engine d may be used for that purpose (to drive the shaft n and the parts connected therewith) and to that end 75 the following arrangement of parts is provided: Mounted in a hanger 87 depending from a transverse frame-member or girder 88 is a short shaft 89 on the front end of which is mounted fast a bevel gear 90 that 80 meshes with the bevel gear e and on the rear end of which is keyed a bevel gear 91 that may, as hereinafter described, be thrown into and out of mesh with a bevel gear 92 fast on the lower end of the driving 85 shaft n . Near the driver's seat e^* is fulcrumed on the chassis a a clutch-lever 93 which is connected with the upper end of a clutch-arm 94 by a link 95. The clutch-arm 94 is mounted free to swing on the chassis 90 a and its forked lower end engages the grooved hub of the bevel gear 91, which is free to slide lengthwise on the shaft 89, being keyed thereto. Hence, by operating the clutch-lever 93 the engine d may be connected with and disconnected from the driving shaft n .

To connect the transverse shaft e' with the engine d so that the latter may drive the former and thereby propel the machine 100 along the highway, a clutch-disk e'' is keyed to the transverse shaft e' adjacent to the hub of the idle bevel-gear e and is adapted to be thrown into and out of engagement therewith by the following mechanism: A 105 bell-crank lever 96 is fulcrumed on a transverse girder or beam 97 (Fig. 2) and one of its arms 96' enters a groove in the hub of the clutch-disk e'' , while its other arm 96'' is connected by a link-rod 98 with a 110 clutch-lever 99 at the lower end thereof. The upper end of this clutch-lever 99 is located within reach of the driver.

The engine d is shown conventionally as an internal combustion engine and the heat 115 from the waste gases or exhaust gases may be utilized in melting the snow in the tank 68. To accomplish this purpose, the exhaust pipe 100 leads from the engine d into the tank 68 and is formed into a coil 101 which 120 surrounds the shell 52 of the triturator 53. The exhaust gases are finally discharged below the bottom of the tank at 102.

The vehicle is provided with the usual steering-wheel 103 and steering mechanism 125 104, which are shown merely conventionally. The casing f is provided with supports or hangers 105 for the inlet hose-pipe q and with hangers 76'' on which rest extra section 76' of the discharge hose-pipe 76. 130

The operation of my new snow-destroying machine may be briefly described as follows: The driving shaft *n* is rotated by means of the water-wheel *h* or the engine *d* or by both these prime movers and in turn drives the conveyer-shaft *z'* and the hollow shaft 14. The latter turns the cutter or disintegrator 4. Snow is shoveled by the laborers into the hopper 28 and is fed by gravity through the 5 guard-rods *u* and the knives 7 to the conveyer *z*. The guard-rods *u* serve to keep the knives 7 from contact with large pieces of stone or other hard substances which would be liable to injure them. The conveyer *z* carries the snow up to and forces it through the 10 grating 37. In case pieces of stone, ice or other hard material pass through between the guard-rods *u*, the pressure exerted by the conveyer *z* will suffice to break them into very small fragments, the ribs 38 of the 15 grating 37 being edged on the face of the latter opposed to the conveyer *z*. The sweep 39 brushes the snow from the upper face of the grating 37 into the chute 2 and water flowing from the water-pipe 44 through the 20 perforations 45 therein assists gravity in moving the mass to the discharge end 3 of the chute. The mouth 3 of the latter is kept clear by means of the inclined plates or 25 vanes *i'* on the arms of the water-wheel *h*. The snow falls into the chamber *i* and is carried downward by the screw-conveyer 57, by which it is forced through the stationary 30 grating 58. It is next subjected to the 35 triturating action of the knives 64, 65 and is reduced practically to the form of water. The water discharged from the water-wheel *h* will assist in the melting process. The liquid mass will overflow from the tank 68 and 40 will flow down the helically-inclined surfaces 69 into the discharge chute 70, where the paddles or blades 72 will pulverize any lumps still remaining in the liquid mass, while at the same time these blades assist 45 the movement of the latter toward the discharge end of the chute.

It is to be observed that, in my new snow-destroyer hereinbefore described, the liquefacent action upon the snow in the triturator is the resultant of the disintegrating or disrupting action of the water discharged with great force against the snow and the triturating action of the knives which act upon the snow in the presence of the water 50 which fills up the tank in which the triturator is mounted and into which it discharges. The material which overflows the upper edge of the tank is that upon which the parts of the machine have acted the longest prior to the overflow and which is, therefore, the best prepared for discharge. Since the action of the knives of the triturator upon the snow takes place in the presence of an excess of water and, moreover, of 55 water in motion, the snow is subjected to

disintegration under the most favorable conditions for its rapid and thorough breaking up and its discharge in a highly fluent state.

I claim:

1. In an apparatus of the character described, the combination of triturating mechanism; means for feeding the material to said mechanism; means for supplying water to the latter; and a discharge device for the triturated material. 70

2. In an apparatus of the character described, the combination of triturating mechanism; means for feeding the material to said mechanism; a discharge chute for the triturated material; and reducing mechanism mounted in said chute. 80

3. In an apparatus of the character described, the combination of triturating mechanism; a conveyer for feeding the material to said mechanism; means for supplying the material to said conveyer; and a discharge device for the triturated material. 85

4. In an apparatus of the character described, the combination of triturating mechanism; a conveyer for feeding the material thereto; a hopper; a disintegrator for cutting the material in its passage from the hopper to the conveyer; and a discharge device for the triturated material. 90

5. In an apparatus of the character described, the combination of a hopper; a conveyer; a disintegrator for cutting the material in its passage from said hopper to said conveyer; and means for driving the latter. 95

6. In an apparatus of the character described, the combination of a hopper; a conveyer for removing the material from the same; and mechanism for giving said hopper a vibratory motion. 100

7. In an apparatus of the character described, the combination of a hopper; a conveyer for removing the material from the same; a disintegrator for cutting the material in its passage from said hopper to said conveyer; and means for moving said conveyer and disintegrator in opposite directions. 105

8. In an apparatus of the character described, the combination of a hopper; a conveyer for removing the material from the same; a disintegrator for cutting the material in its passage from said hopper to said conveyer; means for driving the latter and said disintegrator; and guard devices arranged outside of said disintegrator. 110

9. In an apparatus of the character described, the combination with a conveyer; of a grating through which the conveyer forces the material to disintegrate the same. 115

10. In an apparatus of the character described, the combination with a conveyer; of a grating through which the conveyer forces the material to disintegrate the same; and a sweep for removing the disintegrated material from the grating. 125

11. In an apparatus of the character described, the combination with a conveyer; of a grating through which the conveyer forces the material to disintegrate the same; and a sweep for removing the disintegrated material from the grating; said sweep being provided with devices for further reducing the material. 70
12. In an apparatus of the character described, the combination with a conveyer; of a chute for the material conveyed by the latter; and a flushing device for supplying water to flush away the material. 75
13. In an apparatus of the character described, the combination with a conveyer; of a grating through which the conveyer forces the material to disintegrate the same; a chute; and a sweep for driving the material from said grating into said chute. 80
14. In an apparatus of the character described, the combination with a conveyer; of a grating through which the conveyer forces the material to disintegrate the same; a chute; a sweep for driving the material from said grating into said chute; and a device for supplying water to the material after its disintegration. 85
15. In an apparatus of the character described, the combination with a conveyer; of a chute for the material conveyed thereby; and means for keeping unobstructed the discharge end of said chute. 90
16. In an apparatus of the character described, the combination of a conveyer; a chute for the material conveyed thereby; triturating mechanism to which said chute leads the material; and means for discharging the triturated material. 95
17. In an apparatus of the character described, the combination of a hopper; a conveyer for removing the material therefrom; triturating mechanism for reducing the material; and a discharge device for the triturated material. 100
18. In an apparatus of the character described, the combination of a hopper; a conveyer for removing the material therefrom; a grating through which the conveyer forces the material to disintegrate the same; triturating mechanism for further reducing the material; and a discharge device for the triturated material. 110
19. In an apparatus of the character described, the combination of a hopper; a conveyer for removing the material therefrom; a grating through which the conveyer forces the material to disintegrate the same; a sweep for clearing the material from off said grating; triturating mechanism for further reducing the material; and a discharge device for the triturated material. 120
20. In an apparatus of the character described, the combination of a hopper; a conveyer for removing the material therefrom; a disintegrator for cutting the material in its passage from said hopper to said conveyer; and a grating through which said conveyer forces the material to still further disintegrate the same. 125
21. In an apparatus of the character described, the combination with feeding mechanism; of a pair of cutter-carrying triturating mechanisms; and means for moving one of said triturating mechanisms relatively to the other. 130
22. In an apparatus of the character described, the combination with feeding mechanism; of a pair of triturating mechanisms; means for moving one of said mechanisms relatively to the other; and means for supplying water to the material. 135
23. In an apparatus of the character described, the combination with feeding mechanism; of a pair of triturating mechanisms; means for moving one of said mechanisms relatively to the other; a discharge chute for carrying away the triturated material; and mechanism mounted in said chute for still further reducing the material. 140
24. An apparatus of the character described, consisting of snow-reducing devices; a water motor for driving the same; a vehicle which carries said devices; mechanism for propelling said vehicle; and means for connecting and disconnecting said water motor and mechanism to and from each other. 145
25. An apparatus of the character described, consisting of snow-reducing devices; an engine for driving the same; and means for leading the exhaust from said engine through said devices to the outer air. 150
26. An apparatus of the character described, consisting of snow-reducing devices; a vehicle which carries the same; a motor for driving said devices; an engine; and means for connecting said motor and engine to and from said propelling mechanism. 155
27. An apparatus of the character described, consisting of feeding mechanism; triturating mechanism to which the material is fed by the latter; means for supplying water to the material; and a discharge device for leading the triturated material away from the apparatus. 160
28. In an apparatus of the character described, the combination with triturating mechanism; of a tank within which the latter is arranged; and means for leading the triturated material away from said tank. 165
29. In an apparatus of the character described, the combination with triturating mechanism; of a tank within which the latter is arranged; means for supplying water to the material; and means for leading the triturated material away from said tank. 170
30. In an apparatus of the character described, the combination with triturating mechanism; of a tank within which the latter is arranged; and a casing into which said 175

tank empties and which leads the triturated material therefrom.

31. In an apparatus of the character described, the combination with triturating mechanism; of a tank within which the latter is arranged; means for supplying water to the material; and a casing into which said tank empties and which leads the triturated material therefrom.
- 10 32. In an apparatus of the character described, the combination of a tank; a triturator which is mounted in and discharges into said tank, the upper edge of the latter being arranged above the outlet of said triturator; and means for leading away the overflow of triturated material from said tank.

33. In an apparatus of the character described, the combination of a tank; a triturator which is mounted in and discharges into said tank, the upper edge of the latter being arranged above the outlet of said triturator; and means for leading away the overflow of triturated material from said tank.

34. In an apparatus of the character described, the combination of a tank; a triturator which is mounted in and discharges into said tank, the upper edge of the latter being arranged above the outlet of said triturator; means for leading away the overflow of triturated material from said tank; and snow-reducing mechanism into which said means discharge.

35. The combination with snow-reducing devices; of a water-motor for driving the same, the water discharged from said water-motor flushing away the reduced material.

36. The combination with a triturator; of a water-motor which drives the same and discharges water thereinto upon the material under trituration.

37. The combination with snow-reducing devices; of a motor for driving the same, said motor having mounted thereon snow-feeding means.

38. The combination with snow-reducing devices; of a water-motor which drives the same and which discharges water upon the material acted upon; said water-motor being provided with snow-feeding means.

39. The combination with triturating devices; of a grating; mechanism for forcing the material through said grating to said devices; and means for driving the latter and said mechanism.

40. The combination with triturating devices; of a grating; mechanism for forcing the material through said grating to said devices; means for driving the latter and said mechanism; and means for supplying water to the material under trituration.

41. The combination with triturating devices; of a grating; mechanism for forcing

the material through said grating to said devices; and a water-motor which drives the latter and said mechanism and which discharges water upon the material under trituration.

42. In an apparatus of the character described, the combination of a hopper; a conveyor for removing the material therefrom; triturating mechanism for reducing the material; a discharge device for the triturated material; and means which connect said hopper and discharge device and through which the fluent contents of the former are emptied into the latter.

43. In an apparatus of the character described, the combination of a tank; a triturator which is mounted in and which discharges into said tank; an engine; a pipe mounted in said tank and connected with said engine for leading the exhaust therefrom; and discharge means into which said tank overflows.

44. In an apparatus of the character described, a triturator and a casing therefor; said casing having openings provided with air-tight closures.

45. An apparatus of the character described, consisting of a vehicle; snow-reducing devices mounted thereon; a motor for driving said devices; an engine; mechanism for propelling said vehicle; and means for coupling and uncoupling said engine to and from said devices and mechanism.

46. An apparatus of the character described, consisting of a vehicle; snow-reducing devices mounted thereon; a water-motor for driving said devices; an engine; mechanism for propelling said vehicle; and means for coupling and uncoupling said engine to and from said devices and mechanism.

47. In combination in an apparatus of the character described, snow-reducing devices; a water-motor for driving the same; a hydrant; a conduit leading therefrom; and discharge devices connected with said conduit and arranged to direct streams of water against said water-motor.

48. In combination in an apparatus of the character described, snow-reducing devices; a motor which is provided with vanes and which drives the said devices; a source of fluid under pressure; and means for directing the fluid against said vanes to drive said motor; the latter discharging the fluid into said devices.

In testimony whereof I hereunto set my hand this eighth day of September, 1910, at New York city, N. Y., in the presence of the two undersigned witnesses.

PATRICK D. RIORDAN.

Witnesses:

JAMES HAMILTON,
EMMA I. McCARTHY.
